Primary Examiner—Celia Murphy**Attorney, Agent, or Firm—Fish & Richardson P.C.****[57] CLAIM**

The ornamental design for a shoe sole, as shown and described.

DESCRIPTION

FIG. 1 is a plan view of a shoe sole showing my new design; FIG. 2 is a left side view thereof; FIG. 3 is a right side view thereof; FIG. 4 is a front view thereof; FIG. 5 is a rear view thereof; FIG. 6 is a top view thereof; and, FIG. 7 is a sectional view along line 7—7 of FIG. 1. The dotted line showings of a sidewall of a sole in FIGS. 1 and 2 are for illustrative purposes only and do not form any part of the claimed design.
